REFRIGERATOR CAR

Filed May 21, 1923

2 Sheets-Sheet 2

UNITED STATES PATENT OFFICE.

VICTOR WILLOUGHBY, OF RIDGEWOOD, NEW JERSEY, ASSIGNOR TO AMERICAN CAR AND FOUNDRY COMPANY, OF NEW YORK, N. Y., A CORPORATION OF NEW JERSEY.

REFRIGERATOR CAR.

Application filed May 21, 1923. Serial No. 640,411.

The accompanying drawings illustrate the preferred form of the invention, though it is to be understood that the invention is not limited to the exact details of construction shown and described, as it is obvious that various modifications thereof within the scope of the claims will occur to persons skilled in the art.

In said drawings:

Fig. 1 is a partial vertical section partly broken away, of a refrigerator car constructed in accordance with this invention;

Fig. 2 is a horizontal section through part of the side and end walls of the structure shown in Fig. 1;

Fig. 3 is a horizontal section on an enlarged scale of a wall of the structure shown in Figs. 1 and 2 taken at a post and showing the manner of securing the insulating layers which form the walls;

Fig. 4 is a view similar to Fig. 3 and showing a modified construction of wall; and

Fig. 5 is a view similar to Fig. 3 and showing a further modification of the wall construction.

It is an object of this invention to provide a refrigerator car of improved construction and more particularly to provide a refrigerator car wherein the heat insulating material constitutes the walls of the car and reinforces the posts and braces in carrying the wall strain. It is also an object of this invention to provide an insulating wall which is comparatively light and of great strength and which may be quickly and cheaply made and applied. It is also an object of this invention to provide a refrigerator car wall without the usual dead air spaces thereby decreasing the wall thickness and increasing the car capacity.

As shown in the drawings, the car comprises the usual underframe having the center sills 1 and the side sills 2 joined by body bolsters 3 and cross bearers 4. To the side sills are secured the Z-shaped side posts 5 and braces 6 while to the end sill 7 are secured the end posts 8 and at the corners are secured the angle corner posts 30, the up-

per ends of the side posts 5, the braces 6 and the corner posts 30 being secured to the angle fascia plates 9. Upon the underframe is placed a sub-floor 10 upon which is placed a layer of water proofing material 11 which may be a water proofing paper or a suitable water proofing compound floated thereon.

Upon the water proofing 11 are placed a plurality of sheets or layers 12 of cellular fibrous material which has been thoroughly matted or felted in the manufacturing process and pressed into rigid self-sustaining sheets of light weight and capable of carrying considerable loads. The layers 12 are protected by a layer 13 of suitable water proofing material. The heat insulating material 12 is set in a short distance from the sides and ends of the floor 10 in order to provide space for the nailing strips 14 upon which is placed the main floor 15. The floor 15 is spaced from the insulating material 12 a suitable distance so that nails used in securing objects to the floor 15 will not puncture the water proofing 13 and the heat insulating material 12.

Secured to a number of the posts by bolts 16 are furring strips 17 and secured to the top of the furring strips and to the posts are nailing strips 18 to which is secured the wood ceiling 19 upon which are placed a plurality of layers 12 of the heat insulating material. The layers 12 upon the ceiling are held in position by strips 20 which are engaged by the carlines 21 secured to the posts 5 and supporting the roof 22.

The construction of the side and end walls is identical. Referring more particularly to a side wall, each wall comprises a plurality of layers 12, of which the layers *a* and *b* are placed between the furring strips 17 and the posts 5 and extend outside the nailing strip 14 to engage with the sub-floor 10 at the side sills. At its upper edge the inner layer *b* extends in back of the fascia plate 9 while the outer layer *a* stops just short of the fascia plate, leakage from the fascia plate into the wall being prevented by the water shed 23 which extends from between the fascia plate and the layer *b* of heat in-

sulating material beneath the fascia plate and projects downwardly a short distance in front the outer heat insulating layer *a*. These two layers of heat insulating material 5 have staggered joints, the joints in each instance coming in back of one of the posts and the layers being secured together at the post by nails which are driven through the two layers and clenched.

10 The furring strips 17 are shouldered as at 24 and extending between the furring strips are a plurality of layers of heat insulating material, there being as shown in Fig. 3, the two layers *c* and *d*, which are held in engagement with the outer layers *a* and *b* by the shoulders 24 of the furring strips and which are secured to the outer two layers by nails. The layers *e* and *f* extend between the furring strips and are held in position by the 15 layers *g* and *h* which are nailed to the furring strips. As shown in Fig. 3 the layers *g* and *h* of heat insulating material also have staggered joints, the joints in each instance coming in line with the furring strips so 20 that the edges of the sheets of insulating material may be properly secured to the furring strips.

In the modification shown in Fig. 4 the inner layer *h* of heat insulating material is 25 replaced by a wood sheathing 25 which is provided to protect the heat insulating material from the contents of the car. In the modification shown in Fig. 5 the furring strip 170 is not shouldered and some of the 30 layers of heat insulating material 12 are replaced by layers 26 of hair felt or similar material clamped in place by the furring strips while the inner layer of heat insulating material is replaced by the wood 35 sheathing 25 as in Fig. 4. In each case, however, all the layers with the exception of the two outer layers *a* and *b* extend between the floor 15 and wood ceiling 19 and have their 40 edges secured by the nailing strips 27 and 28.

45 It will be seen that this invention provides a car wall in which there are no dead air spaces and which is composed substantially entirely of heat insulating material and which in conjunction with the posts and 50 braces will withstand the usual strains to which a car wall is subjected, the laminations or layers 12 of heat insulating material being sufficiently rigid and strong to be self-sustaining and to contribute materially to 55 the strength of the car walls.

What is claimed is:

1. In a refrigerator car, posts and a laminated outer heat insulating wall formed of a plurality of fabricated cellular sheets 60 carried by said posts, the laminations adjacent transversely of the wall contacting with each other.

2. In a car, posts, furring strips secured to said posts, heat insulating layers extending between said furring strips and heat

insulating layers extending past said furring strips and securing said first mentioned layers in position.

3. In a car, posts, layers of heat insulating material secured together and engaging 70 said posts, shouldered furring strips secured to said posts and clamping said layers of heat insulating material in position, layers of heat insulating material mounted freely between said furring strips and a layer of 75 heat insulating material secured to said furring strips and securing said freely mounted layers in position.

4. In a refrigerator car, posts, vertical furring strips secured to said posts, a plurality of rigid layers of self-sustaining fabricated cellular heat insulating material 80 clamped between the furring strips and the posts by means securing the furring strips to the posts.

5. In a car, posts, furring strips secured to said posts, heat insulating layers clamped to said posts by said furring strips, heat insulating layers filling the spaces between said strips and heat insulating layers secured to 90 said strips and holding in place the layers between the strips.

6. In a refrigerator car, posts, furring strips secured to said posts, layers of heat insulating material having staggered joints 95 clamped to said posts by said strips, layers of heat insulating material extending between said strips and a layer of heat insulating material secured to said furring strips and holding the second mentioned 100 layers of insulating material in place between the furring strips.

7. In a car, posts, layers of heat insulating material engaging said posts, shouldered furring strips secured to said posts and 105 clamping said layers in position, additional layers of heat insulating material held in position by the shoulders on said strips, layers of heat insulating material extending between said furring strips and a layer of 110 heat insulating material secured to said strips and holding the layers extending between the strips in position.

8. In a car, a side sill, a fascia plate, posts connecting said side sill and fascia plate, layers of heat insulating material secured to said posts and extending between said side sill and fascia plate, a floor and a ceiling engaging said heat insulating material and additional layers of heat insulating material 115 extending between said floor and ceiling and secured to said first mentioned layers of heat insulating material.

9. In a car, a side sill, a fascia plate, posts connecting said side sill and fascia plate, heat insulating material secured to said posts 120 extending in back of said fascia plate and a water shed means secured between said plate and insulating material and projecting downwardly below said plate.

10. In a refrigerator car, posts, vertical furring strips secured to the posts and a self-sustaining outer wall of rigid laminations of fabricated cellular insulating material secured together and to said strips, certain of said layers extending between the strips and other layers extending beyond the strips.
11. In a car, metallic posts, laminations of self sustaining heat insulating material secured to said posts by heat conducting means and parallel self-sustaining laminations of heat insulating material connected with said first mentioned laminations only.
12. In a refrigerator car, a trussed side wall comprising a side sill, a side plate, posts and diagonal braces connecting the sill and side plate and a laminated insulation plate structure comprising vertical wood furring strips and a plurality of load sustaining sheets of fabricated cellular fibrous material joined to the posts by securing means passing through the posts and the furring strips.
13. In a refrigerator car, a truss girder side wall comprising an insulating wall plate of fabricated load sustaining cellular fibrous sheets, furring strips between some of the sheets, a side sill, a side plate, metallic posts and diagonals connecting the sills and side plate and means for connecting the furring strips and posts and holding between them one of said sheets.
14. In a refrigerator car, a metallic truss structure comprising side sill, side plate, posts and diagonal braces and a laminated wall comprising a plurality of parallel fabricated cellular sheets, vertical furring strips enclosed between said sheets and means directly connecting the furring strips to said posts.
15. In a refrigerator car, a side wall comprising an open metallic truss having posts and a laminated insulation plate structure comprising a wood lining, wood furring strips and a plurality of load sustaining sheets of fabricated cellular fibrous material joined to the posts by securing means passing through the posts and the furring strips.
16. In a refrigerator car a truss girder side wall comprising an insulating wall plate of fabricated load sustaining cellular fibrous sheets, furring strips between some of the sheets, a wood lining secured to said sheets, a side sill, a side plate, metallic posts and diagonals connecting the sill and side plate and means for connecting the furring strips and posts thereby clamping between them some of said sheets.
17. In a refrigerator car, a metallic truss structure comprising side sill, side plate, posts and diagonal braces and a laminated wall comprising a plurality of parallel fabricated cellular sheets, vertical furring strips enclosed between said sheets and means extending through some of said sheets and directly connecting the furring strips to said posts, thereby clamping said sheets between the furring strips and the posts.
18. In a refrigerator car, vertical wall posts of Z-section, a laminated insulation wall plate structure comprising a plurality of sheets of fabricated cellular fibrous material joined to the posts by securing means passing through the sheets, the posts, the furring strips and through a sheet of hair felt thereby clamping the hair felt in position.
19. In a refrigerator car, a truss girder side wall comprising an insulating wall plate of fabricated cellular fibrous sheets, furring strips between some of the sheets, a side sill, a side plate, metallic posts connecting the sill and side plate, a sheet of hair felt between the posts and one of the cellular sheets and means for connecting the furring strips and posts and holding between them the hair felt.
20. In a refrigerator car, a laminated wall comprising a plurality of parallel fabricated cellular sheets, vertical furring strips enclosed between said sheets, vertical car framing posts on the outer side of said wall and means directly connecting the furring strips and cellular sheets to said posts.
21. In a refrigerator car, a side wall comprising a side plate, posts and diagonal braces connecting the sill and side plate and including a laminated insulation plate structure comprising vertical wood furring strips, hair felt and a plurality of load sustaining sheets of fabricated cellular fibrous material joined to the posts by securing means passing through the posts and the furring strips, thereby clamping the hair felt in position.
22. In a refrigerator car, a truss girder side wall comprising an insulating wall plate of fabricated load sustaining cellular fibrous sheets, furring strips between some of the sheets, a sheet of hair felt in contact with said furring strips, a side sill, a side plate, metallic posts and diagonals connecting the sill and side plate and means for connecting the furring strips and posts and holding between them one of said cellular sheets and a sheet of hair felt.
23. In a refrigerator car, a metallic truss structure comprising side sill, side plate, posts and diagonal braces and a laminated wall comprising a plurality of parallel fabricated cellular sheets, a sheet of hair felt between said cellular sheets, vertical furring strips enclosed between said sheets in contact with said hair felt and means directly connecting the furring strips to said posts.
24. In a refrigerator car, a side sill, vertical posts and diagonal braces, a wood lining, substantially vertically extending furring strips between the posts and wood lining and self supporting laminations of fabricated cellular insulation secured between

the posts and furring strips, between the furring strips and said wood lining and means connecting the furring strips and said posts.

5 25. In a car, posts, furring strips secured to said posts and spaced therefrom, heat insulating layers extending between said

furring strips and heat insulating layers extending past said furring strips and between said furring strips and posts and securing 10 said first-mentioned layers in position.

In witness whereof I have hereunto set my hand.

VICTOR WILLOUGHBY.
